C. J. HAGSTROM

AUTOMATIC WEATHER STRIP FOR CLOSURES

Filed April 17, 1922

UNITED STATES PATENT OFFICE.

CARL JOHN HAGSTROM, OF GLEN COVE, NEW YORK.

AUTOMATIC WEATHER STRIP FOR CLOSURES.

Application filed April 17, 1922. Serial No. 553,416.

To all whom it may concern:

Be it known that I, CARL JOHN HAGSTROM, a citizen of the United States, residing at Glen Cove, in the county of Nassau and 5 State of New York, have invented certain new and useful Improvements in Automatic Weather Strips for Closures, of which the following is a specification.

This invention relates to builders' hardware and has particular reference to weather strips for movable closures, such as case- 10 ment doors, windows, or other like parts of a building.

Among the objects of the invention is to 15 provide a weather strip of a relatively rigid nature carried by and movable with respect to a closure as stated, the weather strip being adapted in the closed position of the door, window, or other like closure to hug snugly 20 against the sill, frame, or saddle.

Another object of the invention is to provide a weather strip having a hinged or movable connection with a closure with means for controlling the movement thereof around 25 its axis coincident with the swinging of the closure on its hinges.

With the foregoing and other objects in view the invention consists in the arrangement and combination of parts hereinafter 30 described and claimed, and while the invention is not restricted to the exact details of construction disclosed or suggested herein, still for the purpose of illustrating a practical embodiment thereof reference is had to 35 the accompanying drawings, in which like reference characters designate the same parts in the several views, and in which:

Figure 1 is an inside elevation of a door equipped with the invention.

40 Fig. 2 is an enlarged fragmentary vertical section taken approximately on the line 2—2 of Fig. 1 with the door in closed position.

Fig. 3 is an enlarged fragmentary vertical section through the door, illustrating the 45 same in closed position.

Fig. 4 is a similar view illustrating the door in a partially open position.

Fig. 5 is a vertical transverse section on the line 5—5 of Fig. 3.

50 Fig. 6 is a vertical section on the line 6—6 of Fig. 4.

Referring now more specifically to the drawings I show a closure 10 mounted to swing around vertical hinges 11 in a frame 55 12 and over a sill or saddle 13. By the

term "closure" as used herein I wish to be understood as covering broadly any analogous building element such as a French case- 60 ment, swinging window, door, or the like.

The weather strip 14 is preferably made 65 of sheet metal or its equivalent, bent to form a hook shaped flange 15 along its upper edge, while the main portion of the strip may have any configuration, depending upon the edge of the saddle with which it is 70 adapted to co-operate when the closure is shut. As indicated, however, the strip is shown as being bent along a longitudinal line parallel to the hook 15 forming an ob- 75 tuse angle for co-operation with an undercut channel or groove 13' formed in the outer edge of the sill.

Any suitable means may be provided to so connect the strip 14 to the closure as to provide for swinging movement thereof 75 around a horizontal axis substantially within or parallel to the hook 15. The strip is adapted to lie in nested or housed position within a channel 16 formed in the lower edge of the closure adjacent to the outside 80 as shown in Fig. 6, or to be ejected or delivered therefrom by gravity or other means into co-operation with the saddle 13 when the closure is closed, as indicated in Fig. 5. The center of gravity of the weather strip 85 is located outside of the axis thereof, and hence the strip will tend to lie naturally against or close to the saddle when the closure is shut, although I desire to employ auxiliary means not only to insure the de- 90 livery downward of the weather strip but the holding thereof in snug contact with the saddle.

The means I prefer to employ for hous- 95 ing the weather strip in the channel 16 is a sheet metal casing 17 having along its inner edge a hook shaped flange 18 providing a trough-like bearing and embracing and supporting the turned up edge or flange 15 of the strip and within which casing the strip is free to rotate. In the open position of the closure the strip will lie entirely within the casing where it may be held either by contact at one end with the saddle or by special simple mechanical means.

As illustrated the means for ejecting the weather strip includes a lever 19 pivoted on a horizontal pivot or bolt 20 within the housing 21. The head 22 of the lever co-operates with a longitudinally shiftable plunger 23 110

which extends through the housing 21 and the adjacent lower part of the closure. A strong spring 24 tends normally to swing the lever 19 to project the free extremity of the plunger from the closure and by reason of a shoulder or lug 19' on the lower end of the lever positively lift an arm 25 with which it engages. This arm 25 is pivoted loosely upon the pivot 20 of the lever 19, and through a link 26 secured to the weather strip 14, thereby swings the weather strip on its horizontal axis to nest within the channel 16 and casing 17. The link 26 extends through a slot 27 in the bottom of the housing 17. As the closure is being shut the free end of the plunger 23 will engage the side of the frame and effect a longitudinal inward movement thereof as shown in Fig. 3, putting the spring 24 under tension, while an auxiliary lighter spring 24', through the medium of the arm 25 and link 26, tends to force the strip 14 downward into snug but resilient engagement with the saddle, assisted by gravity. The auxiliary spring will permit the strip to be lifted even though the lever be held as in Fig. 3. When the closure is open the plunger 23 is released, and under action of the main spring 24 the same will be shifted longitudinally outward, thereby permitting the main spring to lift and house the strip as in Fig. 6, to an out of the way position, and against the force of the spring 24'.

As above pointed out I may employ mechanical means in co-operation with the weather strip to force the same downward when the closure is shut. As shown in Fig. 2, I provide a combined locking bolt and actuator, the bolt being indicated at 28 for co-operation with the saddle 13 to lock the closure shut and the actuator being indicated at 29 in the form of a finger connected rigidly with a side of the bolt 28. The actuator being movable downward through the upper portion of the casing 17, the end of the finger or actuator pushes downward against the upper and outer surface of the weather strip and moves it positively into closed position when the end of the bolt enters the socket 30 formed in the saddle. Any suitable means may be provided to control the action of the bolt 28. As shown the upper end of the bolt is toothed at 31 for co-operation with a pinion 32 carried by the shaft of a manipulation knob 33. The rotation of the knob to unlock or release the bolt from the saddle will naturally release the finger 29 from the weather strip and so the weather strip will be free to swing upward with the opening of the closure as already described.

The saddle is shown made of metal, grooved or corrugated on top to prevent slipping thereon, and having a groove 13' on its outer edge below the groove 13, whereby rain or the like will be effectively de-

flected from flowing or creeping over the saddle.

I claim:

1. The combination with a closure and a casing secured in the edge of the closure, 70 said casing having a trough-like bearing at its inner edge, of a weather strip having a turned up edge forming a flange having movable mounting in the bearing, whereby the strip may be housed wholly in the casing or projected therefrom.

2. The combination with a support having an inclosure therein, of a movable weather strip mounted in said inclosure, a pivoted spring pressed arm connected to the weather strip to project the same from said inclosure, a pivoted member engaging the arm, a spring engaging said last mentioned member to overcome the first mentioned spring and hold the weather strip in its inclosure, and a device moved by movement of the support into closed position to move the said member and permit the spring pressed arm to force the weather strip from its inclosure. 80

3. The combination with a support having an inclosure therein, of a movable weather strip mounted in said inclosure, a pivoted spring pressed arm connected to the weather strip to project the same from said inclosure, a pivoted member engaging the arm, a spring engaging said last mentioned member to overcome the first mentioned spring and hold the weather strip in its inclosure, and a longitudinally movable plunger forced in one direction by the closing operation of 90 the support to move the member to permit the spring pressed arm to force the weather strip from the inclosure.

4. The combination with a closure and a pivoted weather strip therein and adapted to swing outward around its axis from one edge thereof, of a locking bolt carried by the closure and movable in a direction perpendicular to said axis, and a rigid finger fixed upon the locking bolt and projecting laterally therefrom and thence parallel thereto for engaging the weather strip to force it around its axis into snug operative position when the locking bolt is projected into locking position. 100

5. The combination with a closure, of a weather strip at the base of the closure and movable around a horizontal axis, a vertically movable locking bolt carried by the closure and having a finger projecting therefrom to engage the weather strip to force the latter into snug operative position when the bolt is moved into locking position, manually operated means for moving the bolt, and mechanical means for moving the 110 weather strip in the opposite direction when permitted by the unlocking movement of the bolt and its finger.

In testimony whereof I affix my signature.
CARL JOHN HAGSTROM.
